INVENTOR.
BY
George C. Heuer
ATTORNEY

UNITED STATES PATENT OFFICE.

KAZIMIERZ J. KRUKOWSKI, OF WEST HAMMOND, ILLINOIS.

WRENCH.

Application filed June 2, 1922. Serial No. 565,369.

To all whom it may concern:

Be it known that I, KAZIMIERZ J. KRUKOWSKI, a citizen of the United States, residing at West Hammond, county of Cook, 5 and State of Illinois, have invented certain new and useful Improvements in Wrenches, of which the following is a specification.

This invention relates to improvements in wrenches, and has for its principal object to 10 provide a wrench having means for holding the sliding jaw and for allowing a ready and instantaneous release of this holding means in order to adjust the wrench to the varying sizes of work pieces.

15 A further object of the invention is the provision of a wrench of a novel and extremely simple and inexpensive construction which has all the advantages of an adjustable wrench, and embodies also the features 20 of a quick moving jaw wrench.

With these ends in view, this invention consists in the details of construction and combination of elements hereinafter set forth and then specifically designated by 25 the claim.

In the accompanying drawing, forming a material part of this disclosure, a preferred form of my invention is illustrated, and in this drawing:-

30 Figure 1 is a side elevation of a wrench constructed according to the present invention.

Figure 2 is a section along line 2—2 of Figure 1.

35 Figure 3 is a cross-section on line 3—3 of Figure 1, and

Figure 4 illustrates in detail top plan and side views an operating member.

As illustrated in Figs. 1 and 2, the wrench 40 comprises a stationary jaw 10' and a movable jaw 10', the former having a handle extension 12 and the latter an extension 13 slidably fitted within the handle extension. The stationary jaw has a body portion 11 45 adapted to be secured to the handle extension 12 by screws 14.

The body 11 has near its lower end a rectangular recess 16, open at the front and in this recess a vertically disposed worm 17 is 50 located in engagement with the teeth of a rack 18 on the lower end of the shank 13 of

movable jaw 10'. Through this worm 17 the pin 19 of an operating member 20 is guided, the upper end of which extends into a suitable socket in body 11 above recess 16.

55

The member 20 has an angular slot 21 in its side faces in which a pin 22 of body 11 travels, and the outer end of the member 20 is formed with a shoulder 23 from which a pin 24 projects, and with a corrugated grip 60 25.

The handle 12 is also formed with an inner shoulder 26 provided with a socket for the reception of a spring 27, with which the pin 24 engages when the parts are in the 65 position illustrated in Figure 1.

The device operates as follows:

When it is desired to quickly adjust the wrench to a work piece, the member 20 is pulled down so that its end or pin 19 becomes disengaged from the body 11, and allows a disengagement of worm 17 from rack 18, so that now the movable jaw 10' can be adjusted in its relative position with respect to jaw 10, whereafter the pin 19 is 75 again brought into engagement with the socket in body 11. During this manipulation the pin 22 of body 11 will be guided within the angular slot 21 of member 20 to limit and guide the movements of the movable jaw.

As indicated in dotted lines in Figure 1, the jaws may be square instead of rounded.

Having thus described my invention, what I claim as new, and desire to secure by Letters Patent of the United States is-

A wrench, comprising a fixed jaw and a movable jaw, said fixed jaw having a handle extension and said movable jaw having an extension slidably fitted within said handle 90 extension, said fixed jaw being formed with a rectangular recess to expose a rack formed on the extension of the movable jaw, a worm arranged in said recess to cooperate with the teeth of said rack, a pin rotatably supporting said worm, said pin being extended in part beyond the fixed jaw and formed to provide a handle, to permit endwise movement of said pin at will, a spring arranged between said handle and fixed jaw to move 100 the handle and thereby the pin in one direction, said pin being formed with an angu-

larly related slot having a lower portion in parallelism with the pin and an upper portion at an angle thereto, and a member carried by the fixed jaw to engage in said slot, whereby in the movement of the pin by the handle that portion of the pin carrying the worm and the worm is moved laterally to

disconnect the worm and rack to permit quick adjustment of the movable jaw relative to the fixed jaw.

In testimony whereof I have affixed my signature.

KAZIMIERZ J. KRUKOWSKI.
